[57] ABSTRACT

A synthetic fuel gas is produced from crude oil by a combination of inter-related steps which separate the oil into several fractions, a first ethane and lighter gaseous fraction, a further gas fraction containing propane and butane, a gasoline containing fraction boiling up to, about 400° F., and a heavy oil or residual fraction, the first two fractions are treated with caustic to remove sulfur and sulfur compounds therefrom, the third fraction is hydrodesulfurized and the fourth fraction is catalytically cracked to extinction to produce gaseous products and an additional gasoline fraction which is hydrodesulfurized whereupon all except the first fraction are combined and then converted by known operation to produce a synthetic natural gas or fuel. This gas or fuel can be combined with the first gas fraction either before or after hydrogen has been removed from it.

5 Claims, 1 Drawing Figure

**PROCESS FOR MAKING SYNTHETIC FUEL GAS
FROM CRUDE OIL**

SYNTHETIC FUEL GAS FROM CRUDE OIL

This invention relates to the production of a synthetic fuel gas or a synthetic natural gas from a crude oil.

In one of its concepts, the invention provides a process for converting a crude oil substantially entirely into a fuel gas or synthetic natural gas by steps involving distilling or otherwise separating a crude oil into at least the following streams: a gas stream containing some ethane and lighter gases including hydrogen, a stream containing essentially propane and butane, a stream containing gasoline and boiling up to about 400° F and a heavy residual stream, the first two streams being treated as in a caustic treater to remove sulfur and sulfur compounds therefrom, the third stream obtained being hydrodesulfurized and the last stream being catalytically cracked to extinction to produce gaseous products and an additional gasoline stream which is hydrodesulfurized whereupon all except the first gaseous stream are combined and gasified under conditions known in the art to produce a synthetic natural gas which can be combined with the first obtained gas stream either before or after hydrogen has been removed therefrom thus having converted substantially all of the crude oil to a synthetic fuel gas or synthetic natural gas.

The pending shortage of natural gas makes it imperative to develop methods for converting the plentiful fossil fuels to a synthetic fuel or natural gas. It is known to convert coal, tar sands, bitumen, shale oil, crude oil, pitch, in fact, almost any material containing hydrogen and/or carbon to a synthetic fuel or natural gas.

I have now conceived a process for the conversion of a crude oil into a fuel gas. In the process there are employed inter-related steps in a combination which economically and advantageously treats all of the crude oil in several fractions, under optimum conditions for each, to produce a combined feedstock for a synthetic natural gas or fuel gas production operation.

It is an object of this invention to provide a process for the conversion of a crude oil. It is another object of this invention to provide a process for the production of a synthetic fuel gas or synthetic natural gas. It is a still further object of the invention to provide a process for the conversion of a crude oil substantially completely to a fuel gas or synthetic natural gas. It is a still further object of the invention to provide a process in which steps are so interrelated as to economically and advantageously substantially completely convert a crude oil to a fuel gas or synthetic natural gas in considerably simplified manner.

Other aspects, concepts, objects and the several advantages of the invention are apparent from a study of this disclosure, the drawing and the appended claims.

According to the present invention, a crude oil is separated into several fractions containing components according to their distillation or fractionation boiling points, each fraction is treated under optimum conditions to produce a gas fraction, a gaseous hydrocarbon fraction, a liquid hydrocarbon fraction boiling up to about, say, 400° F and a top crude or heavy residual fraction, converting the heavy residual fraction by catalytic cracking substantially to an additional gaseous fraction and a gasoline fraction, treating each of the streams, however the crude oil is separated into its

constituents, or separated into fractions or streams, to remove sulfur and/or sulfur containing compounds therefrom, combining at least the substantially liquid streams obtained and feeding the combined streams as charge stock to a synthetic natural gas or fuel gas production operation and later, as desired, combining product thus obtained with one or more of the remaining streams obtained to produce a synthetic fuel gas or a synthetic natural gas.

10 The present invention converts a crude oil into a fuel gas or to a synthetic natural gas by an especially attractive route. It employs a minimum of well-developed steps.

15 Referring to the drawing in which is illustrated diagrammatically a flow plan of the invention, a complete crude oil is charged to a crude distillation unit wherein it is separated into several, e.g., four product streams. A single distillation zone 1 is shown for simplicity. Crude oil entering at 2 is heated and flashed to separate light components from an unvaporized heavier portion. The light gaseous components are then passed via pipe 3 directly to treater 14 while the liquid residue is fractionated in crude fractionator 2. Depending on the 20 nature of the crude charge, the degree of sharpness of separation desired, the crude fractionator may comprise two or even more fractionation towers, as one skilled in the art will know. Crude oil fractionation is well known in the art.

25 The distillation unit is designed to produce each of the four product streams with a specified composition especially suited for the conversion of each into a synthetic natural gas. Usually there will be used a preflash tower and a distillation column. Thus, the overhead product stream 3 will be obtained from the flash tower

30 and will contain ethane and lighter components. Therefore, according to the invention, it will need only to be desulfurized before use as a fuel gas. The remaining heavier components in the flash tower bottoms in the original crude oil are reduced in molecular weight and

35 are treated separately from overhead stream 3 as follows: The propane and butane in the crude oil are separated as a second product from the distillation unit

40 2 as stream 4. This stream is easily desulfurized in the liquid state by caustic scrubbing in treater 13. This treatment is more economical than hydrodesulfurization. A C₅ to about 400° F fraction is passed by 5 from the distillation unit to hydrodesulfurizing zone 12. This material can be converted to fuel gas without a preliminary cracking step. This fraction is desulfurized by catalytic hydrogenation in zone 12. The remaining heavy components of the crude oil, the about 400° F- 45 plus fraction, is cracked before conversion to fuel gas. This is done in heavy oil catalytic cracker 7 which, though it is like a conventional catalytic cracker, is

50 operated under more severe cracking conditions to crack the heaviest components of the crude oil. Products of the cracking step are: light gases which are combined by 8 with stream 3 from the distillation unit; a propane-butane stream which is combined by 9 with stream 4 from the distillation unit; and a catalytic gasoline stream 10. The gasoline stream 10 is desulfurized by hydrogenation in unit 11 (similar to unit 12) and is then ready for conversion to fuel gas. All heavier components are recycled and cracked to extinction.

55 60 65 It is known to steam reform heavy hydrocarbons to produce a fuel gas containing in excess of 70 percent methane as disclosed in U.S. Pat. No. 3,506,417. This process uses as feedstock hydrocarbons boiling up to

about 500°F. Heavy oil catalytic cracker unit 7 converts the heavy portion of the crude oil to such lower boiling material. Streams 18, 19, and 20 are combined and the blend passed into steam reforming unit 21 for conversion to fuel gas.

Thus a complete crude oil is fractionated into at least four fractions for advantageous conversion of each to a feed suitable for conversion to a fuel gas in a single gasifier or steam reforming unit. The invention is additionally illustrated by the following example:

EXAMPLE

A Kuwait crude oil with following composition is converted to synthetic natural gas as illustrated in the figure:

36.5° API gravity
 2.5 weight percent sulfur
 0.1 volume percent ethane and lighter
 0.9 volume percent propane
 1.9 volume percent butanes
 24.6 volume percent pentanes through 400° F B.P.
 22.5 volume percent 400° F through 650° F B.P.
 30.0 volume percent 650° F through 1050° F B.P.
 20.0 volume percent residuum

The crude oil in stream 2 after conventional desalting and heat exchange with bottoms stream 6 is passed at the rate of about 200,000 barrels per day into the lower portion of a preflash tower which distills as an overhead product all light components and the majority of the gasoline. The heavier components are reheated in a furnace coil and are passed into the lower portion of crude oil fractionator. The separation of crude oil into a plurality of cuts according to boiling point is practiced in oil refineries and specific details of such operations are known. U.S. Pat. Nos. 3,567,628; 3,303,127; 3,301,778; and 3,297,566 give details of crude oil fractionation. The preflash tower produces an overhead gaseous product stream containing ethane through light gasoline. The overhead flash vapors are conventionally processed by oil absorption and fractionation to yield stream 3 consisting of ethane and lighter components at the rate of about 200 barrels per day (300,000 cu. ft. per day). Stream 4 consisting of propane and butane at the rate of about 5,600 barrels per day is also recovered from the flash tower overhead. The remaining heavier components in the flash tower overhead are recovered as light gasoline and combined with similar material from the crude fractionator as stream 5 amounting to 49,200 barrels per day of material boiling from about 300° to about 400° F. Temperature at the top of the preflash tower is about 320° F. The reduced crude which is yielded as bottom product of the preflash tower is heated in a furnace coil to about 700° F and introduced to the crude oil fractionator. The heavier gasoline fraction (300°-400° F boiling range) is yielded as overhead product of the fractionator. Temperature at the top of this fractionator is 330° F. The remainder of the crude charged to the fractionator, that is, material boiling above 400° F, is withdrawn as bottoms stream 6 at a rate of 145,000 barrels per day.

The preflash tower herein contains a total of eight liquid-vapor contacting trays. Distillation tower contains a total of 34 liquid-vapor contacting trays. Both are operated at essentially atmospheric pressure and at the temperatures given above.

The bottoms stream 6 is converted to gaseous product stream 8 consisting of ethane and lighter in the

amount of about 87,400,000 cu. ft. per day; propane-butane product stream 9 amounting to about 48,980 barrels per day; and catalytically cracked gasoline stream 10 in the amount of about 115,000 barrels per day.

It is known to crack hydrocarbon fluids catalytically to increase the quantity and quality of the gasoline or motor fuel product. It is known to crack topped crude such as stream 6 from fractionator 2 as disclosed in 10 U.S. Pat. Nos. 3,254,019 and 3,303,123. Such a cracking unit operates at more severe cracking conditions in order to completely convert all heavy components to gasoline. The cracking unit 7 operates as in U.S. Pat. No. 3,303,123 with a catalyst-to-oil weight ratio of 15 about 13 to 1, a feed temperature of about 365° F, steam addition of about 75,000 pounds per hour, an outlet temperature of about 960° F, and a feedstock conversion of about 57 weight percent per pass. Fractionation facilities, not shown, are provided for separation of unreacted or incompletely reacted feedstock from the gasoline product and recycle of the unreacted material to the cracking unit.

25 A conventional cracking catalyst, silica-alumina, may be used in cracking unit 7. Others such as synthetic or natural clays, bauxite, and the like can be used. The new zeolite-type catalysts are especially attractive.

Hydrodesulfurization of gasoline stream 10 in unit 11 is effected under conditions known in the art for removal of sulfur compounds. Hydrodesulfurization of 30 liquid hydrocarbon streams is illustrated in U.S. Pat. Nos. 3,487,011 and 2,951,807. Thus, gasoline stream 10 is contacted with a cobalt molybdate catalyst (3 percent cobalt oxide and 15 percent molybdenum oxide) deposited upon activated alumina in the presence of hydrogen at a temperature of about 680° F, a pressure of about 600 psig, a space velocity of about 4 volumes of gasoline per volume of catalyst per hour and a hydrogen rate of about 4,000 standard cubic feet per barrel of gasoline feedstock. The sulfur content is 35 reduced from about 1 percent to less than 0.05 weight percent, and the bromine number is reduced from about 75 to about 3.

40 Hydrodesulfurization unit 12 converts sulfur compounds in straight-run gasoline stream 5 by the same type of catalytic treatment as employed in unit 11. Streams 5 and 10 can be combined and passed through a single desulfurization unit such as 11, depending upon the degree of refinement of the operation desired.

45 Propane-butane streams 4 and 9 are desulfurized in 50 treater 13 by a conventional caustic scrubbing procedure as disclosed in U.S. Pat. No. 3,474,027. The propane-butane stream in the liquid state is countercurrently contacted with a suitable strength aqueous caustic (NaOH) solution at a temperature of about 95° F and a pressure of about 130 psig. A packed or tray-type tower is used with a residence time for the hydrocarbon of about 10 minutes. The caustic solution contains about 19 weight percent NaOH upon entering the contactor. The spent caustic is stripped as described in 55 U.S. Pat. No. 3,474,027 and the regenerated caustic recycled to the treater.

60 Treater 14 also operates like treater 13. The feed-stream is made up of streams 3 and 8 and is in the gaseous state. Thus, a vapor-liquid contact is made in treater 14 between the gaseous hydrocarbon and the liquid caustic. Effluent stream 15 from treater 14 amounts to about 87,000,000 cubic feet per day and has a composition as follows:

Stream 15		Mol %
Hydrogen		52
Methane		40
Ethane		7
Propane		1
		100

Stream 15 can be used directly as a fuel gas. It can be blended with other natural or synthetic gases, or it may be passed through hydrogen recovery unit 16 for separation of the contained hydrogen. Unit 16 is a conventional cryogenic unit wherein the gaseous feedstock is cooled to a sufficiently low temperature to liquefy all components except the hydrogen. Cooling is accomplished by heat exchange with an external refrigeration system such as the methane-ethane-propane cascade refrigeration system of U.S. Pat. No. 3,020,723. Refrigeration can also be accomplished by heat exchange of the ingoing feedstock with the cold products of the step as in U.S. Pat. No. 3,223,745. By this optional procedure, a total of 45,000,000 cubic feet per day of hydrogen can be recovered for use in hydrodesulfurization units 11 and 12. Stream 17 resulting after hydrogen removal is a valuable fuel gas stream. It consists almost entirely of methane and ethane as can be seen from the preceding table.

Additional hydrogen, if needed in desulfurization units 11 and 12, is obtained by partial oxidation of heavy oils being recycled to extinction in catalytic cracker unit 7. Such processes are well known and need not be detailed here.

The three liquid, desulfurized streams 18, and 19, 35 and 20 are combined and converted to synthetic natural gas in gasification unit 21. Such a unit is described in U.S. Pat. No. 3,506,417. It consists of a process for the production of methane-containing gases fungible with natural gas from a nonmethane feedstock which comprises contacting said feedstock and steam at a temperature below about 1000°F with an alkali metal on a nickel and silica-containing support, alkaline earth metal promoted catalyst on a nickel and silica-containing or an alkali metal or a supported platinum group 45 metal catalyst, e.g., platinum on silica-alumina can also be used. The reforming temperature employed usually will not exceed about 1000°F and preferably is in the range of from about 650° to about 1000°F. The reaction pressure will ordinarily be sufficient to maintain liquid-phase conditions, such as from about 100 psig to about 500 psig. The steam to hydrocarbon molecular ratio ordinarily is at least about 2.5 to 1, and generally in the range of from about 2.5 to about 6 to 1. The total gaseous hourly space velocity (GHSV) ordinarily 55 ranges from about 500 to about 40,000 volumes of gas per volume of catalyst per hour, calculated at 32°F and one atmosphere.

The nickel catalyst used in the process is preferably a nickel-kieselguhr catalyst containing from about 5 to about 90 weight percent nickel on a reduced basis and about 0.5 to about 10 weight percent alkali or alkaline earth metal. In this application, the values for weight percent are based on the total weight of the catalyst. Instead of kieselguhr, other natural or synthetic silica-containing material, such as silica, silica-alumina, silica-zirconia, the natural or synthetic crystalline aluminosilicates, and the like, can be used. The alkali metal

or alkaline earth metal can be applied to the catalyst as the hydroxide, carbonate, or other soluble salt. Potassium carbonate is a presently preferred alkaline material.

5 The nickel catalyst exhibits a considerably longer catalyst life than is obtained with known nickel-alumina catalyst. The longer life is now attributed to the fact that a silica-containing support is considerably more stable in the presence of steam than an alumina-containing support.

The platinum group metals can be ruthenium, rhodium, osmium, iridium, platinum, palladium, or mixture of such metals and/or their compounds can be used. Ruthenium is a presently preferred platinum group metal.

10 The platinum group metals can be incorporated into any of the known natural or synthetic refractory inorganic oxide materials known as supports such as alumina, silica, magnesia, zirconia, silica-alumina, the natural or crystalline aluminosilicates, and the like. The amount of platinum group metal present in the catalyst composition can vary from about 0.01 to about 20 weight percent, preferably in amounts less than about 15 10 percent by weight. The amount of alkali metal or alkaline earth metal present in the catalyst can range from about 0.5 to about 10 weight percent. The alkali metal or alkaline earth metal can be applied as hydroxide, carbonate, or other soluble salt. The term "soluble" is intended to include either aqueous or nonaqueous solvents, although water is presently preferred. Potassium carbonate is the presently preferred alkali or alkaline earth compound.

20 As is demonstrated by the specific example hereinbelow, steam reforming of hydrocarbons results in a gaseous product fungible with natural gas, which product contains as much as 70-92 mole percent methane.

25 Combined streams 18, 19 and 20 amounting to 218,780 barrels per day of liquids ranging from propane to components with a boiling point of 500° F are passed to gasifier unit 21 containing a fixed-bed catalyst of an alkali metal-promoted nickel kieselguhr in the form of one-eighth inch pellets. The nickel content is 72 weight percent (after reduction) and the potassium carbonate content is 1.6 weight percent (equivalent to 0.9 weight percent potassium). It is prepared by impregnating kieselguhr with an aqueous solution of a soluble nickel salt, calcining, impregnating with aqueous potassium carbonate, calcining, and reducing in hydrogen for about 7 hours at 650° F and 1 hour at 840° F. Reaction conditions are as follows:

Temp., °F	840
Pressure, psig	325
GHSV, Total	818
Steam/hydrocarbon mole ratio	4.0

Effluent gas composition (stream 22) is as follows:

Component	Mole % (Dry)
Hydrogen	7.0
Methane	77.1
Carbon Monoxide	0.3
Carbon Dioxide	15.6

60 65 The above gas stream 22 can be used directly as fuel gas, may have the carbon dioxide removed as by scrub-

bing with amine solutions and then used as a fuel gas, and can be blended with other fuel gases.

Thus, 200,000 barrels per day of crude oil is converted to 1,066,000,000 cubic feet of fuel gas per day with little or no production of by-products.

The disclosures of patents noted herein are incorporated by reference.

In my process, the residual cut or topped crude is catalytically cracked at rather high temperatures to produce the maximum possible amount of gaseous, olefinic components. The catalytic unit in which the cracking operation is conducted is under conditions to produce mainly synthetic natural gas and therefore the usual good cracking catalyst in the normal context is not needed. There is no advantage to keeping low level of metals on the catalyst. In fact, conditions normally desirable for catalytic cracking to produce liquid products are not preferred in this invention.

The invention is particularly applicable to convert imported heavy oils to maximum gas. While no two crude oils have precisely the same composition, they may all be converted to synthetic natural gas by my invention. The sequence of steps is the same regardless of whether the crude oil contains a high or low percentage of heavy components or a high or low percentage of paraffins, naphthenes, etc. The relative amounts of the fractions obtained in fractionating the crude will, of course, vary but the treatment of the fractions is the same. Thus a very heavy crude oil will have a larger residual fraction passing through the heavy oil catalytic cracker while a light crude oil will have a smaller fraction requiring this treatment.

Reasonable variation and modification are possible within the scope of the foregoing disclosure, the drawing and appended claims to the invention the essence of which is that a crude oil is fractionated or distilled into several streams, each stream is treated under optimum conditions to remove sulfur and/or sulfur compounds therefrom, a residual stream is however first catalytically cracked substantially to extinction following which the cracked products are hydrodesulfurized, several of the streams are combined and gasified or

converted to a synthetic fuel gas or synthetic natural gas.

I claim:

1. A process for the conversion of a crude oil to a synthetic natural gas which comprises separating the crude oil into a first fraction containing ethane and lighter gases, a second fraction containing propane and butane, a third fraction which is normally liquid and will contain hydrocarbons boiling up to about 400°F and a fourth residual fraction comprising topped crude oil; treating said first and second fractions to remove sulfur therefrom as sulfur or sulfur compounds; hydrodesulfurizing said third fraction and catalytically cracking substantially to extinction said fourth fraction to obtain a lower boiling product which product is then hydrodesulfurized, thereafter combining at least two of the last three fractions to form a charge stock for a synthetic natural gas producing operation and catalytically converting said charge stock to form a synthetic natural gas.

2. A process according to claim 1 wherein all but the first fraction containing ethane and lighter gases are combined and passed to the synthetic natural gas producing operation.

3. In a process according to claim 1 in which the first fraction containing ethane and lighter hydrocarbons contains substantial hydrogen: removing the hydrogen therefrom and combining the remaining portion of the first fraction with the synthetic natural gas obtained from the synthetic natural gas producing operation.

4. A process according to claim 1 wherein the catalytic cracking of the fourth fraction produces gases containing ethane and lighter hydrocarbons which are combined with the first fraction containing ethane and lighter gases and hydrocarbon gases heavier than ethane which are combined with the second fraction containing propane and butane gases.

5. A process according to claim 4 wherein normally liquid hydrocarbon obtained in the catalytic cracking is combined with the normally liquid hydrocarbon stream boiling up to about 400° F and hydrodesulfurized together therewith.
